UNITED STATES PATENT OFFICE.

DWIGHT S. MARFIELD, OF CINCINNATI, OHIO, ASSIGNOR TO THE BUCKEYE PRODUCTS COMPANY, OF CINCINNATI, OHIO, A CORPORATION OF OHIO.

METAL-MELTING FURNACE.

1,229,494.

Specification of Letters Patent. Patented June 12, 1917.

Application filed January 2, 1917. Serial No. 140,224.

To all whom it may concern:

Be it known that I, DWIGHT S. MARFIELD, a citizen of the United States, residing at Cincinnati, in the county of Hamilton and 5 State of Ohio, have invented certain new and useful Improvements in Metal-Melting Furnaces, of which the following is a specification.

My invention relates to improvements in 10 furnaces for melting metal to be cast.

One of its objects is to provide an improved form of rotatably mounted furnace with improved features of assembly. Another object is to provide an improved form 15 of furnace adapted to attain reverberatory effects, and to conserve the heat, and to enable liquid or gaseous fuels to be employed to advantage.

Another object is to provide improved 20 means to facilitate skimming and pouring of the metal. My invention also comprises certain details of form, combination and arrangement, all of which will be fully set forth in the description of the accompanying 25 drawings, in which:

Figure 1, is a central longitudinal section through a furnace embodying my improvements.

Fig. 2, is a vertical section through the 30 same on line $\alpha\alpha$ of Fig. 1.

Fig. 3, is a view similar to Fig. 2, illustrating the furnace in position for skimming and pouring.

Fig. 4, is a horizontal longitudinal section 35 through a furnace illustrating a modification.

The accompanying drawings illustrate the preferred embodiments of my invention, in 40 Figs. 1 to 3 of which A represents a cylindrical furnace rotatably mounted upon its longitudinal axis. The body of the furnace preferably comprises a cylindrical shell of 45 sheet metal 2, in the interior of which is molded a cylindrical lining 3 of heat and chemical resisting material. The forward 50 end is closed by a metal head 4 having a tubular trunnion 5, said head having molded upon its inner face a disk shaped section of lining material 6 to make close joints with the forward end of the lining section 3 when 55 the head 4 is assembled with and detachably bolted to the cylindrical section 2. The lining section 6 has a central perforation to register with the bore of the trunnion 5.

The opposite end of the cylinder is closed

by means of a metal head 7 having a solid trunnion 8 and a disk shaped lining section 9 to register with the opposite end of the cylindrical lining section 3. The head 7 is retained in position by means of bolts which 60 detachably secure it to the cylindrical section 2.

The trunnions 5 and 8 are rotatably supported in bearings at the upper ends of standards 10 and 11. A worm wheel f is 65 mounted upon the trunnion 8 outside of the standard 11 and is engaged by a worm on shaft 12, journaled to standard 11. The shaft 12 also carries a beveled gear wheel 14 which meshes with a beveled gear 15 on the 70 shaft 16 journaled to standard 11, and rotated by hand by means of hand wheel 17 to rotate the furnace to any desired position.

An air-blast pipe 18 having a controlling damper or gate 19 is loosely connected by 75 means of a telescopic joint 36 and flange joint 37 to the bore of trunnion 5 to discharge a blast of cool or heated air into the furnace to support combustion therein.

A fuel supply pipe 20 to supply liquid, 80 gaseous or pulverulent fuel to the furnace is controlled by means of a cock 21 and enters the bore of trunnion 5 through the wall of the air blast pipe so as to terminate concentrically therewith in the bore of trunnion 5, so as to enable the incoming fuel and air to thoroughly mix as they enter the furnace chamber. Where liquid fuel is employed the air-blast serves to atomize the liquid as it leaves the exit of pipe 20, and 85 for which purpose any desired atomizing apparatus not shown may be employed.

At one side of the furnace, preferably about midway thereof I provide an opening 25 with an inwardly projecting rim or flange 95 26 in one edge of which is a recess 27 to serve as a lip when skimming or pouring the metal. As illustrated this flange and lip are detachably and renewably provided in the form of a thimble 28 conical or with a 100 shoulder outside and with a cylindrical bore inside, seated in corresponding recess in the lining 3 and held in place by means of a metal flange 29 bolted to the casing 2.

The current of air and fuel in process of 105 combustion sweeps substantially along the longitudinal axis of the interior of the furnace to the rear end thereof, where the gaseous currents are deflected and flow close to the walls of the furnace on the return trip 110

toward the point of inlet where they are again deflected and partly join the fresh incoming gases while the excess of gases being practically exhausted of their heat escape 5 through the opening 25. As the gases are deflected from the rear head and return along the walls of the furnace the inwardly projecting rim 26 of the opening 25 deflects said gases around the side of said inwardly 10 projecting rim instead of permitting a premature escape of said gases, and hence insures the gases remaining in the furnace chamber a sufficient length of time to effect complete combustion and to part with the 15 excess heat to the furnace walls before the gases are allowed to pass through the exit. The opening 25 serves as a metal charging orifice, a gas exit orifice, and for skimming and pouring the molten metal. The shape 20 of the furnace interior is such as to reflect and concentrate the radiant heat from all points upon the furnace charge. The furnace is readily detachable and renewable.

In the modification Fig. 4, the bore 35 in 25 the trunnion 5¹ of head 4¹ and lining 6¹ is conical, and the air conduit 18¹¹ and fuel conduit 20¹ are inclined relative to the axis of rotation so that the current of incoming gases sweeps diagonally across the furnace 30 chamber and is then deflected by the lining 9 so as to return along the opposite side wall and thence escape through the exit 25. The inclination of the conduits 18¹¹ and 20¹ may be in horizontal or other plane as desired to secure the best practical results.

The mechanism herein illustrated and described is capable of considerable modification without departing from the principle of my invention.

40 Having described my invention, what I claim is:

1. A furnace having a melting chamber provided at one end with a burner opening and in a wall at substantially right angles 45 thereto with a port for charging and pouring, said port having an annulus at its inner end projecting into said chamber and adapted to baffle the combustible gases as

they sweep along the wall of said chamber toward said port. 50

2. A furnace having a melting chamber and rotatably mounted upon substantially horizontal bearings, an inlet port for fuel and air through one of said bearings, a charging and pouring port leading through the wall of said chamber at substantially right angles to the axis of rotation, said charging port having an annulus at its inner end projecting into said chamber and adapted to baffle the combustible gases as 55 they sweep along the wall of said chamber toward said charging port. 60

3. A furnace having an interior melting chamber and rotatably mounted upon a substantially horizontal axis, an inlet port for fuel and air leading into said chamber along the axis of rotation at one end thereof, and a charging and pouring port in the side wall of the furnace having at its inner end an annulus projecting from the wall of said chamber inwardly, and a pouring lip in 65 said annulus serving to baffle the combustible gases as they sweep along the wall of said chamber toward said charging port. 70

4. A furnace comprising a cylindrical 75 metal shell having a cylindrical refractory lining, metal heads provided with refractory linings and detachably connected to said cylindrical shell at opposite ends thereof to provide a refractory walled melting 80 chamber, trunnions carried by said heads to rotatably support said furnace, an inlet port for fuel and air through one of said trunnions, and an annular thimble detachably seated in a recess through the cylindrical 85 wall of said furnace with its inner end projecting into said melting chamber to form a charging and pouring port and an annulus to baffle the furnace gases as they sweep 90 along the wall of said chamber toward said charging port. 95

DWIGHT S. MARFIELD.
